UNITED STATES PATENT OFFICE.

SOLOMON J. LEVY, OF SAN FRANCISCO, CALIFORNIA.

DESIGN FOR AN AUTOMOBILE TRUNK RACK.

Application filed February 15, 1926. Serial No. 16,521. Term of patent 7 years.

To all whom it may concern:

Be it known that I, SOLOMON J. LEVY, a citizen of the United States, residing in the city of San Francisco, county of San Francisco, State of California, have invented a new, original, and ornamental Design for an Automobile Trunk Rack, of which the following is a specification, reference being

had to the accompanying drawing, forming part hereof.

The figure is a perspective view showing my new design.

I claim:

The ornamental design for an automobile trunk rack as shown.

SOLOMON J. LEVY.
